HIGH-FREQUENCY APPARATUS

John R. Woodyard, Berkeley, Calif., assignor to
 The Sperry Corporation, a corporation of Delaware

Application February 5, 1949, Serial No. 74,837

8 Claims. (Cl. 315—5)

1

The present invention relates to high frequency apparatus and methods for producing high-energy electrically charged particles, and, more particularly, the invention is concerned with such apparatus and methods wherein the electric fields contained within sections of electromagnetic wave guides and/or cavity resonator devices are utilized to energize the discrete particles of a beam of particles.

A principal object of the present invention is to provide new and improved apparatus and methods for producing a high-energy beam of electrically charged particles.

Another object of the present invention is to provide an arrangement for producing a beam of electrons having an energy content of the order of a billion electron-volts useful in medical therapy or for the production of highly penetrating X-rays or for other purposes.

Heretofore there have been employed diverse types of apparatus for producing beams of high-energy charged particles. The known types of apparatus may be divided, for the present discussion, into two general classes, e. g. (1) "round-and-round" or curvilinear accelerators, and (2) linear accelerators.

The first of the above-named classes includes that form of apparatus in which either a static or a variable magnetic field is employed, with or without accompanying electric fields, to whirl electrically charged particles in curved trajectories whereby a progressively increasing amount of energy is absorbed by the charged particles.

This class of acceleration apparatus has proved to be generally satisfactory for the production of electrons of energies up to about 10^8 electron-volts. However, it may be shown that, following the teachings of the prior methods, the production of a beam of electrons having energies about ten times that of the presently attainable energies necessitates electromagnets having pole pieces roughly 80 feet in diameter. Clearly, apparatus of this type is difficult to construct and very expensive for the production of billion-electron-volt beams of electrons.

A further object of this invention, therefore, is to provide a new and improved electron energizing arrangement of the linear type whereby the need for large electromagnets or other sources of intense magnetic fields is substantially eliminated.

The linear types of accelerators heretofore utilized for producing streams of electrically charged particles stemmed originally from the early forms of cathode ray tubes, wherein elec-

2

trons were continuously accelerated in a unidirectional electric field maintained between a cathode and an anode. Due to inherent limitations, the maximum energies obtainable from such unidirectional fields were of the order of a few million electron-volts. To extend the range of the obtainable energies, alternating field types of linear accelerators were used, employing means for intermittently applying accelerating impulses to the particles.

In one form, the electrons of the beam were exposed to the alternating field for a time approximately equal to the time of a half-cycle. In another form, the electrons were acted on by the field a plurality of times, but such accelerating impulses were supplied only during the positive half-cycles of the accelerating field, the particles being shielded from the field during the negative half-cycles so that only half the energy supplied to the field was constructively utilized. Later types of alternating current linear accelerators, of both these latter forms, extended the limit of the obtainable energy by using high frequency electric fields provided by tuned circuits of the lumped parameter type, and, later still, in the distributed parameter type of circuit embodied in cavity resonator apparatus.

An improved electron energizing apparatus is provided by the present invention whereby energies of the order of a billion electron volts are obtained which is, at least, ten times higher than the level previously obtained by prior known means. This high level of electron energy is realized by the projection of an axial electron beam through a cylindrical cavity resonator so excited as to support a standing electromagnetic field whose configuration defines a zero magnetic field in the axial direction and an axial electric field characterized by a large number of half-cycle variations.

The spatial separation of successive half-cycle variations is adjusted to be approximately equal to the free-space half-wavelength at the operating frequency, so that when a beam of electrons, preliminarily accelerated to velocities nearly equal to that of light, is projected axially along the resonator axis, these high velocity electrons traverse the space between successive half-cycle variations in field in substantially the same time that is required for the variations in the electric field to occur. Consequently, a significant portion of the electrons encounter electric fields favorably disposed for imparting energizing impulses to the beam. Hence, after the beam has been subjected to a predetermined high number

of such energizing impulses, corresponding to the number of half-cycle variations of the axial electric field, the energy level of the electrons of the beam reaches high values such as 10^9 electron-volts.

Accordingly, the present invention has for another of its objects the provision of an improved electron energizing apparatus of the linear type wherein cavity resonator means are excited in such a manner as to subject a beam of high velocity electrons projected therethrough in an axial direction to a plurality of energizing impulses during a single transit of the beam through the resonator.

A feature of this invention lies in providing a linear type of electron energizing apparatus with a cavity resonator excited in a resonant mode such that its standing wave pattern defines a zero magnetic field in the axial direction and an axial electric field characterized by a plurality of half-cycle variations and an arrangement within said resonator for adjusting the spatial separation of successive half-cycle variations to a value substantially equal to the free-space half-wavelength at the operating frequency.

Another feature of the present invention is to provide, in an electron energizing arrangement of the above described character, a cylindrical resonator means characterized by the fact that the ratio of the length of resonator to its diameter of cross-section is very high.

A further object of the present invention consists of providing a method of exciting a cavity resonator apparatus whose length is long as compared to its diameter which comprises the step of exciting said cavity resonator in a high order axial electric mode of order $(0, 1, n)$ where n is an integer greater than zero.

A specific feature of the present invention lies in the provision of a plurality of constrictions formed interiorly of electromagnetic wave-energy guides or cavity resonators to reduce the internodal spacings of the electromagnetic field variations.

The constrictions may have a spatial separation equal to the free space half wavelength at the operating frequency, or alternatively continuous loading may be employed by placing a plurality of constrictions along the length of the resonator per half-cycle variation in the standing wave pattern.

An additional object of the present invention is to provide a device for the production of high-energy electrically charged particles, wherein the requisite high-frequency excitation energy is impulsively supplied to the device.

A still further object is to provide means within a wave-energy guide for increasing the velocity of relatively slow-injected electrons so that they may then be acted upon by the electromagnetic field to provide a high-energy beam of electrons.

Still another object of the present invention is to provide an arrangement for producing high-energy electron beams as above, wherein means are provided for symmetrically coupling high-frequency electromagnetic energy from a source to the utilization device wherein coupling is effected at the entrance terminal of the device.

Yet another object of this invention is to provide a symmetrical coupling for high-energy electron beam energizing apparatus of the above-described character wherein the coupling of ex-

citation energy is effected at the exit terminal of the device.

A still further object of the present invention is to provide an arrangement for coupling high-frequency electromagnetic energy to a utilization device having means for distributively coupling the resonator-excitation energy to the resonator so that the coupling is accomplished substantially uniformly along the length of the cavity resonator.

Another object of the invention is to provide a novel coupling arrangement for a utilization device employed for the production of a high-energy electron beam which comprises a combined symmetrical-distributive coupling arrangement whereby undesired modes of oscillation are substantially eliminated.

The invention also relates to the novel features or principles of the instrumentalities described herein, whether or not such are used for the stated objects, or in the stated fields or combinations.

Other objects and advantages will become apparent from the specification taken in connection with the accompanying drawings, wherein the invention is embodied in concrete form.

In the drawings,

Fig. 1 is a diagrammatic representation of the electric field distribution within a metal cylinder;

Fig. 2 is a longitudinal cross sectional view of one embodiment of the present invention together with a schematic showing of the energizing circuit associated therewith;

Figs. 3a and 3b are explanatory graphs of voltages existing at various points of the circuit of Fig. 2.

Fig. 4 is a similar view of another modification of a portion of the interior construction of the resonator of Fig. 2;

Fig. 5 is a longitudinal cross sectional view of a modified form of the device shown in Fig. 2 in which the excitation energy is coupled to the resonator at the entrance terminal thereof;

Fig. 6 is a similar view showing the coupling of the excitation energy at the exit terminal of the resonator;

Fig. 7 is a longitudinal cross sectional view of a modified embodiment of the present invention in which the excitation energy is coupled to the resonator at a plurality of points uniformly distributed along the length of the resonator;

Fig. 8 is a cross sectional view taken along the line 8—8 of Fig. 7;

Fig. 9 is a modification of the arrangement shown in Fig. 7 and shown in longitudinal cross section;

Fig. 10 is a cross sectional view taken along the line 10—10 of Fig. 9; and

Fig. 11 shows another modified embodiment of the present invention wherein coupling of the excitation energy to the electron energizing apparatus is effective in a combined symmetricto-distributive arrangement.

Similar characters of reference are used throughout the figures to indicate corresponding parts.

Referring now to Fig. 1 of the drawing, which is a diagrammatic representation of the instantaneous electromagnetic field distribution of a wave propagated in a wave guide, the reference numeral 21 designates a hollow conducting cylindrical tube through which electromagnetic waves are regarded as being transmitted in a

mode of propagation commonly indicated as $TM_{0,1,0}$. The distributions of the electric and magnetic fields are here shown as lines 22 (corresponding to the electric field distribution) and the circles 24 and dots 26 (corresponding to the magnetic field distribution, the circles 24 indicating lines of magnetic force directed toward the reader and the dots 26 indicating lines of magnetic force directed away from the reader).

It is apparent that this mode of propagation is ideal for accelerating electrons or other charged particles for, if a beam of such particles is projected axially along the tube 21 with a velocity such that the particles in the beam traverse a distance s between the transverse planes indicated by the dashed lines p and q corresponding to regions of zero axial electric field, in a time equal to a half-cycle of the frequency of the energy, then clearly, the electrons, assuming that they are introduced into the guide in phase with the electrical field, will always experience a field favorable for abstraction of energy therefrom.

When a wave guide, such as tube 21, is closed at both ends there results one form of a resonator. Energy which is propagated through such a resonator encounters, in the first instance, one of the conducting end walls interposed in its path, whereupon a reflected wave is set up which travels in an opposite direction. As a result, the incident and reflected waves give rise to a standing wave pattern. In such case, although the electric and magnetic field intensities of the incident wave are in time and space phase coincidence as are the electric and magnetic field intensities of the reflected wave, the resultant electric and magnetic field intensities are in time and space quadrature. From this it is apparent that when electromagnetic energy is propagated in a wave guide terminated in its characteristic impedance, the maxima of the electric and magnetic field intensity variations occur at the same points, as is evidenced by the arrangement of the lines of force of Fig. 1. On the other hand, where the guide is operating as a resonator a 90° spatial separation of the respective maxima of electric and magnetic lines of force diagrammatically represents the field distribution.

Now, it is also known that if the tube 21 be closed by a pair of conducting walls perpendicularly disposed with respect to the axis of the tube 21, one of the walls being placed at the plane p and the other at q , a high-Q cavity resonator is thereby formed having a resonant mode of oscillation known as the $TM_{0,1,1}$ mode. Consequently, in considering the wave guide of Fig. 1 modified by the proposed conducting walls positioned at planes p and q , the location of the lines of force will be altered in the manner described above.

It is further known that a resonator may be constructed of such length that a plurality of half-cycle variations of field intensity may be present normal to the transverse field. In other words, in conventional symbolism the configuration of the field may be defined as the $TM_{0,1,n}$ mode, where n denotes the number of such half-wave patterns. As has been indicated in the prior art, this mode of operation is ideal for the accelerating or energizing of electrons.

A simple numerical example illustrates the nature of the problems encountered and the limits thereby established in prior art devices. Suppose it is desired to obtain electrons having

energies of 10^9 electron-volts by means of a cylindrical cavity resonator excited in the $TM_{0,1,0}$ mode; operations in such a mode would necessitate very high power of excitation. With such magnitude of excitation energy field emission or so-called "low-temperature" emission assumes an important role in the successful maintenance of the standing wave pattern within the resonator. Electron emission that occurs mainly as a result of a strong external field effect on the work function has been frequently described as "field emission." As it is well known, field emission imposes an upper limit on the voltage gradient which can be supported in an evacuated chamber before breakdown. This limit may conservatively be placed at about 10^6 volts per centimeter. Thus, a resonator so excited and energized for the production of 10^9 electron-volt particles would necessarily be about 10^3 centimeters or about 30 feet long.

Theoretically, a cylindrical resonator excited in the $TM_{0,1,0}$ mode may be expanded to such a length since the resonant wavelength is independent of the length of the chamber. However, to be an efficient linear accelerator, it is necessary that the electrons traverse the length of the resonator in a period corresponding to that of a half-cycle of the excitation frequency, so that the electrons may have a maximum net energy gain. To accomplish this, the resonator would necessarily be operated at a wavelength approximately equal to 60 feet, and in accordance with the well-known relationship between the resonant wavelength of such a resonator and its diameter of cross section, the diameter of cross section of such a resonator would necessarily be about 46 feet. Obviously, the utilization of an evacuated cavity resonator of such proportions presents constructional and maintenance problems which raise serious doubts as to the practicability of the device.

In accordance with the present invention it is proposed to operate a cylindrical resonator at a high-order mode designated as the $TM_{0,1,n}$ mode where n is the number of half-cycle variations of the axial electric field. For the present purpose n may be any integer greater than zero and preferably is of the order of 100. Under such circumstances, as pointed out more fully below, it is not necessary for the electrons to traverse the length of the resonator in a time interval corresponding to a half-cycle variation in the excitation frequency. When excited in the $TM_{0,1,n}$ the standing wave configuration within the resonator comprises nodes in the longitudinal component of the electric field, successive ones of which are spaced a distance comparable to, although somewhat greater than the free-space half-wavelength at the operating frequency.

For modes of oscillation of order in which n is greater than zero, it is known that the resonant wavelength is dependent on the length of the resonator as well as on the diameter of cross-section thereof. It may be shown that for a mode characterized by $n=100$, the required diameter of cross section for a resonator of length equal to 30 feet is only several inches provided the wavelength is suitably chosen. Or, assuming that a resonator of a predetermined small diameter as compared with its length is selected for use in the accelerating or energizing apparatus, it has been found that a mode of excitation of sufficiently high order may be found which satisfied the conditions for the maintenance of the desired field.

The fact that the distance between successive nodes in a resonator excited as specified hereinabove, is greater than the free-space half-wavelength poses a further problem to the solution of which the present invention is directed. As pointed out above, a successful linear accelerator or energizer should satisfy the condition that the distance traversed by the electrons in the time of half-cycle of the operating frequency should be equal to the distance between successive nodes in the resonator so that the electrons may always encounter accelerating electric forces. For energies of the order here contemplated the velocity of the electrons is very nearly equal to c , the velocity of light. Thus, the necessary condition to be satisfied may be restated in the following manner: the distance between successive nodes should be equal to the free-space half-wavelength at the operating frequency.

Inasmuch as the internodal distance in the cavity resonator is somewhat greater than the free-space half-wavelength and, since the electrons cannot have velocities greater than c , it is clear that unless the internodal distance within the resonator be reduced to substantially the value of the free-space half-wavelength, electrons will be subjected at times to decelerating force fields as well as accelerating-force fields, thereby seriously reducing the efficiency of the apparatus.

As a solution of the foregoing problem, the present invention provides means within a cavity resonator for precisely fixing the internodal spacing at a value substantially equal to the free-space half-wavelength thereby insuring that the electrons, traveling with a velocity almost equal to that of light, are substantially always in an accelerating-force field.

More specifically, as will appear in the detailed description hereinbelow, a preferred form of this feature comprises a type of alteration of the electromagnetic field existing within the cavity resonator which is accomplished by providing constrictions within the otherwise smooth-wall resonator, the constrictions being so arranged as to reduce the diameter of the resonator by a predetermined amount and through a predetermined length thereof. To produce the desired value of the internodal spacing, the constrictions are disposed in the median planes of the longitudinal electric field, in the region where the radial component of the electric field is a maximum and the axial component is a minimum. A convenient means for producing such constrictions has been found to be in the form of conductive rings mounted within the resonator and extending peripherally therearound.

It will be understood that it is within the contemplation of the present invention that the energy absorbed by the electrons is mainly manifest by increased mass of the electrons. The change in the velocity, at such high velocities is practically negligible. The overall result mainly resides in the increased energy of the particles. However, the apparatus of the present invention will sometimes be called an electron accelerator, even when the acceleration is negligible, in accordance with conventional usage of the word.

To determine the magnitude of the radio frequency power required to obtain electrons having energies of 10^9 electron volts, let us consider a simple numerical example. We have previously found that a cylindrical cavity resonator excited in the $TM_{0,1,0}$ mode would have an approximate length of 10^3 centimeters to provide electrons

having the above-specified energy. This results from the conservative estimate of the possible voltage gradient (10^6 volts per centimeter), which can be successfully maintained in such a resonator. Where the excitation employed is in the $TM_{0,1,0}$ mode it is apparent that a similar overall length of resonator would be required for the production of electrons having a billion electron volts of energy. If the excitation energy supplied to tube 21 has a wavelength equal to 20 cm., a cavity resonator section formed by conducting walls positioned at the points p and q will have a shunt impedance of approximately 10^7 ohms and will be a half-wavelength or 10 cm. long. Accordingly, each of these 10 cm. sections provides 10^7 volts and the peak power per section is given by

$$\frac{E^2}{R} = \frac{(10^7)^2}{10^7} = 10^7 \text{ watts}$$

With the previously determined tube length there will be 100 10 cm. sections, from which it appears that the total peak power required is 10^9 watts. As pointed out below, the use of "peak" power involves certain approximations. If the excitation power supplied is pulsed with a space-to-pulse ratio of 1000 to 1, the average power will be approximately 1000 kw. While this represents a substantial amount of power, it is, however, well within obtainable limits. For instance, several laboratories now have installations capable of delivering power in excess of this quantity.

To obtain electrons having the same energy, it is possible to reduce the requisite amount of excitation energy by the simple expedient of employing a longer tube 21. Within limits, the required power and tube length are inversely proportional. At the same operating frequency electrons having the specified energy are obtainable with a tube length of 10^4 cm. or approximately 300 ft. with an input power of 100 kw. With a constant tube length, the power required varies substantially as the square of the electron energy. Electrons having an energy of approximately 10^9 electron volts are obtainable with a 30 ft. tube with an average power of 10 kw. or a peak power of 10 megawatts.

The above calculations include certain approximations. In arriving at the shunt impedance, copper losses in the assumed end walls of each 10 cm.-section were included, whereas these losses would not occur with the contemplated cavity resonator such as tube 21 having a length equal to numerous half-cycle variations at the operating frequency, as discussed above. Furthermore, no account was taken of the fact that the electrons are not exposed to the peak value of the electric field all of the time in their passage through the tube 21. However, these two errors tend to cancel each other.

The following additional illustrations provide an indication as to the approximate interrelationship of the various design factors. It is assumed that the excitation energy has a wavelength of 20 cm. and the average power, based on a pulsing time ratio of 1000 to 1, will be discussed. Electrons of 100 m. e. v. are obtainable with a 30 ft. resonator operating with a voltage gradient of 10^6 volts per cm. and requiring 10 kw. It will be noted that this arrangement produces an energy equal to that of the largest existing "betatron" and could be constructed at a fraction of the cost of the latter. To procure an energy of 10^9 electron volts a tube length of 300

It, maintaining a voltage gradient of 10^5 volts per cm. with a required power of 100 kw. represents at the present state of the art the best compromise between tube length and input power. For a relatively small installation a tube length of 3 ft. having a gradient of 10^5 volts per cm. with a 1 kw. power input provides an energy of 10 m. e. v. Such an arrangement has numerous commercial possibilities, such as an industrial X-ray equipment for photographing holes in castings and the like. Moreover, inasmuch as such a resonator is only three feet long it can readily be sealed off and the combined equipment will weigh but a few hundred pounds.

In Fig. 2 there is illustrated one embodiment of the invention together with a schematic showing of the energizing circuit associated therewith. A wave guide 27 partially enclosed at both ends with apertured discs 28, 28' and made preferably of copper, copper-plated steel or brass provides a suitable cavity resonator. The internal surfaces of the resonator thus formed are made highly-conducting to minimize power losses in the device. Throughout the length of the guide 7 constrictions may be arranged in the form of annular rings 29 located normally with respect to the longitudinal axis of the guide 27. To avoid spurious field emissions, the inner edges 31 of the rings 29 are preferably rounded. The center-to-center spacing of successive rings 29 is made equal to a half-cycle of the free-space wavelength at the operating frequency so that numerous half-wave sections 32 are formed for the purpose discussed above. At each end of the guide 27 an end section 33 is formed on one side by a ring 29 and on the other by an apertured disc 28. A source of electrons 34, providing a beam which is concentric with the guide 27, is supported within a glass bell or press 36 by a lead-in strut 37. The glass bell 36 is, in turn, connected by a metal-to-glass seal 38 to the end of guide 27. Similarly, at the other end of the guide 27 another glass bell or press 36' is connected with a suitable seal 38 to facilitate the maintenance of the internal vacuum of the assembly.

The electron gun 34 may include the following elements (not shown): a cathode with an electron-emitting surface, an indirect heater and a focusing or current control electrode.

For the control and supply of energy to the equipment, a generator may be employed having the desired output frequency and power intensity, such as a magnetron oscillator 42, pulsed by a pulse generator 43, which is also connected to a delay line 44. The delay line 44 has two leads 46, 47, connected to the cathode lead-in strut 37 and the outer wall of the guide 27, respectively. A coupling device such as an input wave guide 48 having a vacuum-tight seal 49 is employed to transmit energy from the oscillator 42 to the guide 27. In place of the input wave guide 48, a concentric line may be used, in which case it should be properly formed at the point of connection to the guide 27, in a coupling loop, probe or antenna means to effect a transfer of energy to the guide 27.

It is, of course, understood that several oscillators, depending on the desired power input to the guide 27, may be arranged in parallel to augment the energy supply to the input wave guide 48 or other coupling device. Moreover, a plurality of coupling devices making connection with the guide 27 along its length may be fed by one or more oscillators. Where a plurality of coupling devices are used, care should be taken to

insure that the proper phase relationship among the energy introduced into the guide 27 is maintained. To achieve correct balance in this respect, suitable phase shifting apparatus may be employed in conjunction with the various coupling devices.

Where the production of X-rays is desired, a suitable target positioned in the path of the high-energy beam of electrons may be employed. For convenience, an X-ray producing medium, such as target 39 may be mounted within press 36' by means of a supporting member 41. The physical orientation of the target 39 may be selected to provide the most effective utilization. If desired, a positioning mechanism (not shown) may be used in conjunction with the target 39 and associated parts to permit the altering of the position of the target 39 during or preparatory to the operation of the apparatus.

It is, of course, understood that, in the event it is desired to employ directly the high-energy beam of electrons for medical therapy, or other purposes, not only the target 39 but the bell 36' may be dispensed with. In such case, to maintain the internal vacuum, the aperture in end wall 28' may be covered by an electron-permeable substance or the entire end wall may be made of such substance. A light metal, such as magnesium, aluminum or beryllium constitutes such electron-permeable substance. In this connection it should be noted that the electron beam when passing through the exit end of the guide 27 is possessed of an accumulation of considerable energy.

However, where it is desired to obtain a fine control of the energy of the exit beam, both the type and thickness of material may be selected to alter the magnitude of the energy of the exit beam. Indeed, such a substance interposed in the path of the exit beam may be employed independently of any sealing off of the end of guide 7 and solely for energy control purposes. In addition, the entrance end of the guide 27 may be modified by eliminating the glass bell 36. In its place an electron-permeable substance may be used to cover the aperture of end wall 28 with a source of electrons positioned adjacent the input end of the guide 27.

In operation, a beam of electrons emanating from the electron source 34 is periodically projected through the apertured disc 28 and made to traverse the longitudinal axis of the guide 27. Upon entering the guide 27, the electron beam is subjected to the accelerating electromagnetic field maintained therein. With the internodal spacings of the field pattern being maintained substantially equal to the free-space half-wavelength at the operating frequency, electrons entering the guide with a velocity approaching that of light will traverse each half-wavelength section 32 in a time interval equal to the half-cycle variation in the electromagnetic field. As a result, the electrons will always be present in a force field favorable for their increased energy, as previously described in connection with the introductory remarks and Fig. 1.

In order to reduce the power required for the operation of the device, a pulse generator 43 is employed to control or activate the supply of electromagnetic energy from oscillator 42 to the guide 27. At the same time, the pulse generator is employed for activation or energizing the cathode circuit through a delay line 44. Thus, electrons emanating from the electron source 34 are injected into the guide 27 periodically and at

such times when the voltage of the electromagnetic field contained therein has attained a sufficient magnitude. The attaining of sufficient electromagnetic voltage within the guide 27 prior to the injection of the electrons is achieved by reason of the delay line 44 interposed between the electron source 34 and the pulse generator 43.

While in preceding paragraphs it has been indicated that a right circular cylindrical wave guide is effective for propagating an electric mode of the type $TM_{0,1n}$ which type of mode is particularly suitable for the acceleration of electrons, it is of course understood that the wave energy guide 27 may assume other shapes without departing from the spirit of the invention. Furthermore, apart from the conductive annular rings 29, the wave energy guide 27, 96 (the latter in connection with Fig. 11) has been described as being hollow, however, dielectric material may be used in part to obtain desired electrical characteristics. Thus, such a dielectric material may be used to fill merely a part of the guide or the whole thereof.

In the introductory remarks it has been indicated that the electrons may be energized by passage through a resonator. It is, of course, understood that the acceleration of the electrons may be achieved by projecting them through a traveling wave electromagnetic field. In such a case, electrons should be made to ride the wave crest or, stated somewhat differently, have a phase relative to the phase of the electromagnetic field such that they are continually positioned for the absorption of energy from the field.

It will be noted that there is a section 33 having a length substantially equal to the free-space quarter-wavelength at the operating frequency located at the input end of the guide 27. In the event that the electrons emanating from the electron source 34 are injected with some velocity relatively low with respect to that of light, and which is properly related to the level of the radio frequency excitation power, the average velocity of the electrons during the first quarter-wavelength may be approximately one-half the velocity of light. As a consequence, the electrons will arrive at the first node at a time when the cyclically-varying electromagnetic field reverses. Moreover, where the magnitude of the radio frequency energy employed is substantially high, the electrons will arrive at the first node with a velocity very nearly approaching that of light. Once such a velocity is attained by the electrons, there will occur relatively small velocity changes, so that uniform loading, provided by suitably positioned constrictions may be used throughout the remainder of the length of the guide 27. These considerations are equally applicable to any of the other modifications of the present invention described herein.

In Figs. 3a and 3b graphs of the voltages existing at various points in the circuit of Fig. 2 are illustrated. In Fig. 3a there is plotted a wave form of the voltage appearing at the output terminals of the pulse generator 43. As a result of the connection of the pulse generator 43 to the magnetron oscillator 42, the output wave form of the oscillator has the form illustrated by Fig. 3b. As previously described, owing to the delay line which is interposed between the pulse generator 43 and the electron source 34, electrons are not projected through the wave guide 27 until the excitation voltage therein has assumed a sufficient amplitude. In this connection an explanatory numerical example may prove useful. As

previously discussed, with a time ratio of 1000 to 1, it is possible to obtain electrons having the desired energy without employing an excessive high-power excitation energy source. In the event that the time duration of each pulse is made equal to one microsecond, with an excitation wave having a frequency of 15×10^8 cycles per second, there will occur approximately 1500 cyclical variations of the electromagnetic field for each pulse. No attempt has been made to show the building up of the voltage of oscillator 42 to its normal operating output voltage, nor excitation voltage within the guide 27. With a .05 microsecond delay introduced by delay line 44, 75 cyclical variations will occur (based on the above-mentioned operating frequency and pulse durations) prior to the injection of electrons into the guide 27. This delay will compensate for both the voltage of the oscillator 42 as well as the radio frequency excitation voltage within the guide 27 assuming their normal magnitudes. Owing to the fact that electrons will not be introduced into the guide 27 until the voltage has assumed the desired proportions, a part of the excitation energy supplied to the guide 27 during each pulse will necessarily be lost as far as charged particle energization is concerned. However, this is a negligible quantity of power which does not impair the functioning of the device.

While the above numerical example was based on a time ratio of 1000 to 1 for convenient representation, a ratio of 25 to 1 has been employed in Figs. 3a and 3b.

Where it is desired to employ a smaller magnitude of radio frequency power and a source of relatively slow moving electrons, i. e., electrons which have a velocity substantially lower than that of light prior to being introduced into the energizing portion of the apparatus, a wave guide 27 may be formed with tapered constrictions as shown in Fig. 4. To permit the injected electrons which are relatively slow moving to attain substantially the velocity of light, several sections 54, 56, 57, 58, 59 of unequal length are provided adjacent the entrance end of the guide 27, as indicated by the arrow 64. Similarly, where the input radio frequency power to the guide 27 is relatively small in magnitude, the tapering of the successive lengths of the several sections 54, 56, 57, 58, 59 may be advantageously employed. The sections 54, 56, 57, 58, 59 are formed with tapered annular rings 61, 61' having increasing center-to-center spacings along the length of the guide 27 until the axial extent of the last section 62 is substantially equal to the free space half-wavelength at the operating frequency whereupon the constrictions are arranged as described in connection with the major portions of the guide 27 of Fig. 2 or Fig. 3. The initial section 54 formed at the entrance end of the sleeve 27 by end wall 28 and ring 61 has a length somewhat less than one-half the center-to-center distance between rings 61, 61'.

Preferably, the inner diameter of the tapered rings 61, 61' is selected to be progressively larger in the direction of the electron flow. In addition, the width of the tapered rings 61, 61' may be made progressively larger along the length of the guide 27. As discussed previously in connection with the tapered rings 61, 61', the inner edges 63 may be rounded to discourage field emission.

In operation, a beam of electrons is made to traverse the longitudinal axis of the guide 27 in the direction indicated by the arrow 64. Where

relatively slowly injected electrons and where relatively low radio frequency excitation power are employed, the progressively larger longitudinal dimensions of the sections 54, 56, 57, 58, 59 permit the electrons to increase in velocity. To this end, the respective lengths of the sections 54, 56, 57, 58, 59 are selected so that electrons pass through an individual section in a time during which the field is favorable for providing acceleration or gain of energy of the electrons. A 10 transit of one of the sections 54, 56, 57, 58, 59, 62 having been completed, the electrons move into the adjoining section 54, 56, 57, 58, 59, 62, the electromagnetic field of which is suitable for imparting additional acceleration. In this manner an electron is carried along from one section to the next until it has attained a velocity approaching that of light.

Care must be taken to achieve the correct spacing of the successive sections 54, 56, 57, 58, 59, 62 as a function of the initial electron velocity and the imparted acceleration due to the excitation radio frequency fields. Otherwise, an electron may not enter a section 54, 56, 57, 58, 59, 62 at a time favorable for extracting energy from the field and, in fact, may do work on the field, i. e., deliver some of its energy to the electromagnetic field with a resulting loss of energy of the electron. In the ideal case, the electrons will substantially traverse each section in a time corresponding to the half period of the excitation energy.

A symmetrical coupling arrangement for introducing radio frequency excitation power into the apparatus is shown in Fig. 5, which is a modified form of the device of Fig. 2. The excitation energy is coupled to the device at the entrance terminal thereof, providing for the symmetrical coupling of radio frequency power into the apparatus at the end adjacent the electron source.

As described in connection with Fig. 2, a wave guide 27 having highly conductive internal surfaces is divided into sections by means of constrictions which are formed by conductive annular rings 29. With the exception of the end sections 33, the spacing between successive sections is substantially equal to the free-space half-wavelength of the excitation frequency. At the left end of the guide 27 an apertured disc 28 having an internal surface of highly conductive material is provided, thereby forming a free-space one-quarter wavelength section 33 intermediate the inner surface of the disc 28 and the adjacent annular ring 29.

A hollow cylindrical housing 66 coaxial with the guide 27 is connected in an air-tight manner to the disc 28 and forms an enclosure for the symmetrical radio frequency coupling device. For coupling energy to the guide 27, cylindrical coupling sleeves or antenna 67 located coaxially with respect to the guide 27 is arranged preferably extending partially into the adjacently located quarter-wavelength section 33. To energize the antenna 67, a coaxial transmission line 70 having an inner conductor 68 and outer conductor 69, the inner conductor being supported by a one-quarter wavelength shorted stub 71, is arranged extending radially to the guide 27 and the coupling sleeve 67. One end of the outer conductor 69 is connected to the edges of a suitably formed aperture 72 in the housing 66, with the inner conductor 68 connected to and supporting the antenna 67. The other end of the concentric line 70 is connected to a suitable 75

source of radio frequency energy as shown and described in connection with Fig. 2.

While only one coaxial line 70 coupling device is shown, it is, of course, understood that several such lines might be employed. In such case, it is preferable to maintain a symmetrical disposition of the lines feeding the antenna 67, in order to preserve the appropriate phase relationships. However, if unbalance occurs in this respect, adjustable phase shifting devices (not shown) may be included in the coaxial lines.

An electron gun 34, similar to that previously discussed in connection with Fig. 2 is supported from a glass bell or press 73 by a lead-in strut 31. 15 To provide for the maintenance of an internal vacuum, the glass bell 73 is connected by means of an air-tight seal 74 to the end of the housing 66 and forms with a portion of the latter an enclosure for the electron gun 34. Intermediate the antenna 67 and the electron gun 34 an electromagnetic field terminating diaphragm 76 is located normally of the tube 66.

For certain applications, it is important to operate the apparatus without the excitation of 25 certain modes or types of electromagnetic field patterns in the guide 27. A particular advantage of the symmetrical coupling arrangement described above is that certain undesired modes are not excited, that is, those modes which do not have axial symmetry of the electric field.

In operation, a beam of electrons emanating from the electron source 34 is periodically projected through the aperture of field terminating diaphragm 76 and through the coupling 35 sleeve 67. Upon entering the guide 27 the beam of electrons is subjected to the radio frequency fields and is accelerated or energized in its transit therethrough in the manner previously described in connection with Fig. 2. The diaphragm, while permitting the passage of electrons from the electron gun 34 to the resonator 27, minimizes the loss of the excitation energy endwise of the guide 27 in the direction of the press 73.

45 A further modification of the device of Fig. 2 in which the excitation energy is introduced at the terminal end of the wave guide 27 is shown in Fig. 6. This arrangement has the advantage of the symmetrical coupling of radio frequency energy into the guide 27 described in connection with Fig. 5 and at the same time provides a somewhat simpler and more economical construction. As before, the internodal spacings of the field in the guide 27 are made substantially equal to free-space half-wavelength at the operating frequency. An apertured disc 28' together with an adjacent annular ring 29 forms a one-quarter wavelength section 33 at the exit end of the guide 27. For introducing the excitation energy a coaxial transmission line 77 having an inner conductor 78 and an outer conductor 79 is provided, with collar 83, which is rigidly attached to disc 28', supporting line 77. It is understood that a suitable seal will be employed between the collar 83 and outer conductor 79 of the coaxial line 77, and between inner conductor 78 and outer conductor 79, in order to preserve the internal vacuum of the apparatus. A probe antenna 81 which is an extension of the inner conductor 78 projects into the quarter wavelength section 33 at the exit end of the guide 27 and is concentric therewith. To support the inner conductor 78 a dielectric ring 82, having suitable dimensions to prevent spurious reflections of 60 energy, may be provided. Moreover, as an al-

ternative to the dielectric ring 82 or to provide additional support for the inner conductor 78 a one-quarter wave short-circuited stub (not shown) may be employed.

To offer a negligible obstruction to the high energy electrons the antenna 81 and concentric line 71 preferably may be made of some light metal, such as magnesium, aluminum, beryllium, etc. Similarly, if desired, for reasons of manufacturing simplicity or otherwise, the disc 28 may be made of these materials.

If the electrons emanating from the terminal end of the resonator 27 are to be employed for the production of X-rays, a target of suitable material may be positioned along the longitudinal axis of the guide 27 beyond the disc 28.

The above described symmetrical coupling may be employed in conjunction with the coupling arrangement, shown in Fig. 5, where an additional amount of excitation energy is required. In such a case precautionary measures must be taken to obtain the proper phase relationship between the energy supplied both at the input and output end of the guide 27. This proposed arrangement has all the advantages of the symmetrical coupling and at the same time provides for introduction into the apparatus of an increased amount of excitation energy.

The operation of the apparatus shown in Fig. 6 is substantially similar to that previously described in connection with Fig. 2.

In Fig. 7 there is shown a further modification of the present invention in which the excitation energy is coupled to the apparatus at a plurality of points. As previously discussed, the internodal spacing of the electromagnetic energy contained within the wave guide 27' is reduced by the use of suitably disposed rings 29 which preferably have their inner edges 31 rounded. For uniformly distributed excitation, a coaxial transmission line 84 having an inner conductor 86 and an outer conductor 87 is arranged adjacent to the guide 27' along its length. In order to support the inner conductor 86 of the coaxial line 84, quarter wavelength shorted stubs (not shown) or other similar means may be employed.

To introduce radio frequency power from the coaxial line to the resonator, coupling loops 88, 89, 90, 91 are provided which extend through apertures common to walls of the outer conductor 87 and the guide 27'. The ends of each coupling loop are connected to the inner surface of the wall of the outer conductor 87 and the inner surface of the wall of the guide 27', respectively. The sizes of the coupling loops 88-91 are preferably increased along the length of the guide 27' from its entrance terminal to its exit terminal, to minimize the reflection of energy in coaxial line 84, as discussed more fully below. Similarly, the apertures associated with the coupling loops 88-91 may be progressively enlarged to accommodate their respective loops.

It will be noted, as shown more clearly in Fig. 8, that a portion of the walls of the outer conductor 87 and the guide 27' overlap along their lengths in the vicinity of the coupling loops 88-91.

In operation, coaxial line 84 is connected at one end to a source of radio frequency energy, such as the magnetron oscillator 42 shown in Fig. 2. With impedance matching existing between the oscillator 42 and the coaxial line 84 power losses in the line 84 are negligible and an extremely low standing wave ratio is present therein. The coupling loops 88-91 are made progressively

larger throughout the axial extent of the transmission line 84, the size of each loop being selected so that it extracts a predetermined amount of power from the line 84. More specifically, the dimensions of the individual loops are chosen so that a constantly increasing percentage of the power remaining in the transmission line 84 is introduced into the guide 27' by each successive loop 88-91. In this manner, a substantially equal amount of power is introduced into the guide 27' by each of the loops 88 through 91 and, moreover, all of the radio frequency energy is extracted from the line 84 prior to its terminal end. As a result, there is substantially no energy which may be reflected back through the transmission line 84 in the direction of the electromagnetic energy source and, hence, standing waves are substantially avoided in the line 84.

Apart from the specific arrangement for introducing the radio frequency excitation energy into the guide 27', the operation of the device is similar to that described in connection with Fig. 2.

Of course, it is understood that the coaxial line 84 does not necessarily have to extend for the full length of the guide 27', but may at any convenient point be made to extend directly to the electromagnetic source. Such proposed lines may merely be effective for energizing a single or but a few coupling loops, such as the loops 88, 89, 90. Other transmission lines arranged in the manner of line 84 may be employed to excite distinct groups of coupling loops. As a result, a plurality of coaxial line feeding sections such as that shown in Fig. 7 may be employed with a single or a plurality of high frequency generators. In all of the foregoing versions suitable phase shifting apparatus may be advantageously employed in the respectively feeding lines to obtain the proper phase relationship among the input energy.

The distributed input coupling arrangement of Fig. 7 may also be modified by employing a plurality of coaxial lines arranged longitudinally with respect to the guide 27' as shown in Fig. 7 and spaced uniformly around the periphery of the guide 27'. This arrangement provides not only for the uniformly distributed introduction of excitation power into the guide 27', but in addition achieves a symmetrical excitation as well.

In Fig. 9 there is shown a modification of the arrangement of Fig. 7 which also achieves a distributed coupling of the excitation energy to the guide 27'. This embodiment differs from the showing of Fig. 7 essentially in the omission of the coupling loops and the utilization of coupling slots 92, 93, 94 having progressively larger dimensions in the direction of energy propagation along line 84 for effecting a transfer of excitation energy to the guide 27'. The walls of the guide 27' and the outer conductor 87 of the coaxial line 84 are made to overlap in the vicinity of the slots 92, 93, 94 as shown more clearly in Fig. 10.

The operation of this device, as well as possible modifications of the structure, is similar to those described in connection with Figs. 7 and 8.

The distributed coupling disclosed in connection with Figs. 7 through 10 has at least three important advantages: (1) The starting transient at the beginning of each pulse does not have a long duration compared with that of the single coupling arrangements. (2) Undesired modes of the electromagnetic field are suppressed to an even greater extent than with the coupling

methods shown in Figs. 5 and 6. (3) The magnitude of the power introduced into guide 27' by each coupling loop 88 through 91 or each slot 92 through 94 is substantially less than with fewer coupling units, which is an important factor at high power levels.

The preferred embodiment of the present invention, which attains maximum electron energy with great power economy through the use of a symmetrical-distribution coupling of the radio frequency into the wave guide, tapered loading and synchronous pulsing of the excitation energy and the electron source, is illustrated in Fig. 11. In this arrangement the advantages of both the symmetrical and distributive apparatus for introducing the excitation power into the resonator are achieved. Moreover, the tapered loading feature previously described in connection with Fig. 4 is advantageously utilized so that electrons having initial velocities substantially less than the velocity of light may be employed as well as lower excitation energy. Furthermore, provision is made for pulsing both the input energy to the resonator and the electron source, such pulsing being particularly effective for obtaining a high-energy charged particle beam.

A wave guide 96 is provided with constrictions which reduce the internodal spacing of the electromagnetic field, as previously discussed. However, the guide 96 is constituted of a plurality of energy-directing sleeves 97, 98, 99, 101, 102 which divide the guide into a plurality of compartments 103, 104, 106. Each compartment 103, 104, 106 is constituted of an energy-directing sleeve 97, 98, 99, 101, 102 with an enlarged diameter portion 107, 108, 109, 111, 112, respectively, which extends over the sleeve of the adjacent compartment without making physical contact therewith, to provide radially and axially extending annular slots 113, 114, 116, 117, 118. These slots 113, 114, 116, 117, 118 are preferably made to have progressively lower capacitances in the direction of electromagnetic energy propagation so that progressively larger percentages of the power remaining in the enlarged coaxial supply line 119 may be coupled to the wave guide 96. These annular capacitances may be made progressively smaller by progressively increasing the spacing or progressively decreasing the effective areas in the annular capacitance regions, or both.

To support each compartment 103, 104, 106, a plurality of radially extending rods 121 made of an appropriate material, such as of dielectric composition are arranged intermediate the outer wall of the sleeves 97, 98, 99, 101, 102, and the inner wall of the enlarged outer conductor 122. Suitably located apertures 123 are provided in the wall of the outer conductor 122 to accommodate screws 124 for securing one end of the rods 123 thereto. The other end of the rods 123 are flared with their end surfaces suitably faced for cooperating with the outer wall of the sleeves 97, 98, 99, 101, 102. A wave-directing end sleeve 126 is connected with the inner conductor 127 of the constricted-diameter coaxial supply line 128 by means of an inner conductor conical portion 129 and a hollow inner conductor portion 125. Thus, it will be noted that the enlarged coaxial supply line 119 has an inner conductor which is formed by the wave guide 96. For interconnecting the enlarged outer conductor 122 of the enlarged coaxial supply line 119 with the constricted outer conductor 131 of the constricted coaxial supply line 128, an outer conductor conical portion 132

surrounds the inner conductor conical portion 129 of the end sleeve 126, the conical portion 132 being connected to an intermediate outer conductor portion 135 which is coaxial with the hollow inner conductor portion 125.

In order to supply excitation energy to the device, the coaxial supply line 128 is connected to an excitation energy source, such as a magnetron oscillator 42, the output of which is controlled by a pulse generator 43. To provide a source of electrons, which are to be accelerated, an electron source 34 is arranged exterior to both the enlarged coaxial supply line 119, which houses the wave guide 96, and the reduced diameter supply line 128. The electron source, which contains a suitable electron-emitting surface with appropriate potential-fixing elements (not shown), is aligned to insure that the electrons are projected successively through an aperture 138 in the constricted outer conductor 131, the hollow inner conductor portion 125 and thence along the axis of the wave guide 96. In addition to controlling the output of the magnetron oscillator 42, the pulse generator 43 regulates the introduction of electrons into the wave guide 96. It is, of course, understood that electrons may be introduced into the apparatus from the opposite end. However, with this arrangement the form of the constrictions will be somewhat different, as discussed below.

In order to reduce the internodal spacing of the electromagnetic wave contained within wave-energy guide 96, constrictions in the form of annular rings are arranged throughout the length of guide 96. The compartment formed of the end sleeve 126 and compartments 103 and 104, are provided with annular rings 61, 61', 133 in a manner similar to that previously described in connection with Fig. 4. Thus, the rings 61, 61', 133 have increased center-to-center spacings, aperture diameters and widths in the direction of electromagnetic energy propagation. To accommodate the variation in dimensions of the rings 61, 61', 133, the associated sleeves 126, 97, 98, respectively, have appropriate longitudinal dimensions. Thus, in the device of Fig. 11, there has been shown a plurality of compartments 103, 104, suitable for obtaining the tapered loading feature which was described more fully in connection with Fig. 4. It will be, of course, understood that where desired, a greater number of such compartments 103, 104 may be utilized. Where it is desired to inject electrons from the opposite end of the guide 96, the tapered loading rings 61, 61', 133 will be arranged in the opposite order so that the increased center-to-center spacing of the rings 61, 61', 133 will occur in the direction of the path of the electron beam. With such an arrangement, the electron source 34 will be positioned at the opposite end of the guide 96.

Compartments 106 are formed with annular rings 29, which similarly reduce the internodal spacing of the electromagnetic energy contained within the guide 96. Assuming that the electrons travelling longitudinally through the guide 96 have obtained a velocity substantially equal to the velocity of light, the annular rings 29 are arranged in such a manner as to provide internodal spacing substantially equal to the free-space half-wavelength at the operating frequency. In this manner, the desired highly energized beam of charged particles is obtained.

To insure that the internal vacuum of the apparatus is maintained, a glass bell 141 surrounds the enlarged outer conductor 122, a por-

tion of the reduced diameter outer conductor 131 and the electron source 34. A vacuum-tight seal 142 is arranged within the constricted supply line 128 and another vacuum-tight seal 143 connects the outer conductor 131 and the glass bell 141. Additional seals (not shown) may be used to provide a vacuum-tight connection between the wires 144 and the glass bell 141.

Conventional devices, such as short circuited quarter-wavelength lines or stubs (not shown) may be arranged radially to the constricted diameter coaxial supply line 128 to provide support for the inner conductor 127. If desired, one or more supports or struts similar to those used in connection with sleeves 97, 98, 99, 101, 102, may be employed for providing additional support for the end sleeve 126. Furthermore, suppressors of undesired nodes (not shown) may be included in the enlarged coaxial supply line 119. An annular dielectric ring 134, 136, 137, 138, 139 of suitable composition is shown included in the annular slots 113, 114, 116, 117, 118, respectively, to increase the power handling capacity of the coupling units and provide additional support for the sleeves 97, 98, 99, 101, 102. However, if desired, the dielectric rings 134, 136, 137, 138, 139, may be omitted.

In operation, the pulse generator 43 regulates the supply of electromagnetic energy, which emanates from oscillator 42, to the enlarged coaxial supply line 118. At the same time, the pulse generator 43 is effective for controlling the introduction of electrons projected from the electron source 34 into the wave energy guide 96. By reason of the delay line 44 interposed between the pulse generator 43 and the electron source 34 ample opportunity is provided for the electromagnetic energy within the guide 96 to reach the required intensity prior to the introduction of electrons. The electromagnetic excitation energy, which is propagated through the enlarged coaxial supply line 119 is coupled to the wave guide 96 through the annular slots 113, 114, 116, 117, 118. By employing progressively larger slots in the direction of energy propagation an increasing percentage of the power remaining within the enlarged supply line 119 is introduced into the guide 96. With the varied size annular ring 61, 61', 133, electrons introduced with velocities somewhat lower than that of the velocity of light are permitted to absorb sufficient energy from the electromagnetic waves contained within guide 96 to attain a velocity approaching that of light. This action takes place within the end sleeve 126 and the compartments 103, 104. Once the electrons have approached the desired velocity, the constrictions 29 are uniformly arranged, providing an internodal spacing substantially equal to the free-space quarter wave-length at the operating frequency.

Thus, the arrangement shown in Fig. 11 represents the preferred embodiment of the invention and is particularly useful for obtaining electrons which have the desired magnitude of energy. By employing the desired loading, it is possible not only to employ electrons which have velocities substantially lower than that of the velocity of light, but to utilize a smaller magnitude of excitation energy to sufficiently accelerate the electrons to a point where they may be suitably energized by the apparatus. In addition, the simultaneous control of the excitation energy and the source of charged particles permits the construction of an energizer capable of delivering charged particles having energy greatly in excess of anything

heretofore known. The novel symmetrical distributive coupling arrangement is particularly effective for reducing the starting transient at the beginning of each pulse, suppressing undesired modes of electromagnetic propagations and imposing a greatly reduced power load upon each coupling unit. The latter point is particularly significant in apparatus operating at high power levels where voltage breakdown and undesirable heating must be avoided. Thus, the device of Fig. 11 is particularly effective for achieving the major objects of the invention.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. An electron accelerator comprising a source of radio frequency excitation energy, a coaxial transmission line connected to said source of energy, said coaxial line having an enlarged portion, the enlarged inner conductor portion being hollow and comprising a wave guide for maintaining a cyclically-varying high frequency field, said guide having an entrance end, a source of electrons located adjacent said entrance end of said guide, a plurality of annular rings located within and concentric with said guide, and means for projecting said electrons into the entrance end of said guide, the width and the axial spacing of said rings increasing along the length of the guide and the diameters of said rings increasing along the length of said guide, said spacings of said rings approaching the free-space half-wavelength of said high frequency field.

2. In an electron accelerator, a wave guide having internal conductive surfaces and having an entrance end, a source of electrons located adjacent said entrance end of said guide, a symmetrical coupling means for introducing excitation energy into said guide, said coupling means including a coaxial transmission line section having a tubular inner conductor located intermediate said source of electrons and said guide and concentric therewith for the passage of electrons therethrough, said guide having annular rings with center-to-center spacings corresponding to the free-space half-wavelength at the operating frequency whereby the propagation of undesired modes of electromagnetic energy is substantially eliminated.

3. An electron accelerator comprising a source of electrons which are to be accelerated, a wave guide having one end located adjacent said electron source, means for projecting said electrons into said guide, a source of high frequency excitation power, a coaxial line extending along the length of said guide and having a portion of one of its conductors common with the wall of said guide, said coaxial line being connected to said power source, said common portions of said conductor and said wall having a plurality of longitudinally spaced apertures for distributedly introducing excitation energy into said guide.

4. An electron accelerator comprising a wave guide having an internal conductive surface and constrictions for reducing the internodal spacing of an electromagnetic field contained therein, a source of radio frequency excitation power, coaxial line means parallel to the axis of said guide and uniformly distributed round the periphery

of said guide and further having portions of its conductor walls common with the wall of said guide, said coaxial line means being connected to said power source, said common portions of said walls having a plurality of longitudinally spaced apertures, whereby a symmetrical and distributed coupling of said excitation energy into said guide is accomplished.

5. A high power electron accelerator comprising a guide formed of a plurality of coaxial sleeves having internal conductive surfaces, each of said sleeves having an enlarged outer diameter portion at one end for overlapping the adjoining one of said sleeves to provide annular coupling slots, an outer conductor surrounding said guide and coaxial therewith, said outer conductor and the outer wall of said guide forming an enlarged coaxial supply line for supplying electromagnetic energy to said guide, said sleeves having internal annular rings coaxial therewith for reducing the internodal spacing of the electromagnetic energy therein, a portion of said annular rings having increased center-to-center spacings, widths and aperture diameters along the longitudinal axis of said guide in a portion of said sleeves, the remainder of said rings having uniform dimensions and spacings in the remainder of said sleeves, a source of electrons positioned adjacent one end of said guide, an oscillator connected to said enlarged coaxial supply line for supplying thereto said electromagnetic energy, and a pulse generator connected to said oscillator for regulating the introduction of energy into said coaxial line, said pulse generator further being connected to said electron source through a delay line to insure the excitation energy attaining sufficient proportions prior to the introduction of electrons, whereby a high-energy beam of electrons is obtained.

6. An electron accelerator comprising a hollow wave guide having a longitudinal axis, means for producing a stream of electrons and projecting said stream within said guide along said axis, an outer conductor surrounding said wave guide and cooperating with the outer surface thereof to form a coaxial transmission line, said transmission line being adapted to be connected to a source of high frequency electromagnetic wave energy, and means including apertures in the wall of said wave guide for transferring electromagnetic wave energy from said coaxial line to said wave guide, said apertures being radially symmetrical about said axis.

7. An electron accelerator comprising a hollow wave guide having a longitudinal axis, an electron gun adjacent one end of said guide and aligned on said axis to project a stream of electrons along said axis through said guide, a plurality of annular rings located within and concentric with said guide and spaced along said axis, consecutive rings along the initial portion of the length of said guide being of increasing

inner diameters, coupling means including a tubular conductive member coaxial with said guide and located between said electron gun and said end of said guide, a source of high frequency alternating current energy connected to said coupling means, and a pulse generator connected to said alternating current source and to said electron gun to energize said source and said gun periodically.

10 8. An electron accelerator comprising a hollow wave guide having a longitudinal axis, an electron gun adjacent one end of said guide and aligned on said axis to project a stream of electrons along said axis through said guide, coupling means including a tubular conductive member coaxial with said guide and located between said electron gun and said end of said guide, a source of high frequency alternating current energy connected to said coupling means, a pulse generator connected to said alternating current source and said electron gun to energize said source and said gun periodically, and a delay line included in the connection between said pulse generator and said electron gun, the delay of said line being approximately equal to the time required for an electromagnetic field to build up in said wave guide to substantially the full intensity to be produced therein by said alternating current source.
